HAIR ROLLER BASKET AND UTILITY TRAY FOR HAIR STYLISTS

Richard D. Bieurance, 9013 Cedar Ave.,
Minneapolis, Minn.

Filed July 12, 1960, Ser. No. 61,329

Term of patent 3½ years

(Cl. D86—10)

FIG. 1 is a front elevational view of a hair roller basket and utility tray for hair stylists showing my new design; FIG. 2 is a top plan view of the same; and

FIG. 3 is a side elevational view thereof.

FIG. 4 is a side elevational view of the opposite side of the invention as shown in FIG. 3.

FIG. 5 is a rear elevational view.

I claim:

The ornamental design for a hair roller basket and utility tray for hair stylists, substantially as shown.
